UNITED STATES PATENT OFFICE

159,785

SUN GLARE VISOR FOR WINDSHIELDS

Oscar Dale Crocker, Oak Grove, Oreg.

Application January 3, 1950, Serial No. 6,963

Term of patent 14 years

(Cl. D14—6)

To all whom it may concern:

Be it known that I, Oscar Dale Crocker, a citizen of the United States of America residing at Oak Grove, in the county of Clackamas and State of Oregon, have invented a new, original, and ornamental Design for a Sun Glare Visor for Windshields, of which the following is a specification, reference being had to the accompanying drawing, forming a part thereof.

In the drawing, Figure 1 is a view in front elevation of a sun glare visor for windshields showing my new design; and

Figure 2 is a sectional view taken along lines 2—2 of Figure 1 and further showing my new design.

The essential feature of my design resides in the portion shown in solid lines in the drawing,

the dotted line illustration of a windshield being for illustrative purposes only.

I claim:

The ornamental design for a sun glare visor for windshields, as shown and described.

OSCAR DALE CROCKER.
